SEPARABLE FASTENER

Davis Marinsky, New York, N. Y., assignor to
 Whitehall Patents Corporation, New York,
 N. Y., a corporation of New York

Application August 17, 1932, Serial No. 629,094

12 Claims. (Cl. 24—205)

This invention relates to separable fasteners of the type employing two stringers, and a coupling member or slider slidably engaging the stringers in coupling and uncoupling the same; and the object of the invention is to provide stringers for fasteners of the class specified with a mounting and/or finishing tape so constructed as to cover one side face of the stringer and part of the coupling elements thereon so that in coupling the stringers together the coupling elements will be concealed from at least one side face of the stringer; a further object being to provide a finishing strip of the class specified having a longitudinal line of openings through which the coupling elements of the stringer are adapted to pass in mounting the strip upon the stringer, the strip being provided with a flange portion adjacent the openings formed therein adapted to overlie the coupling elements and to be held in close proximity thereto in the flexing of the stringers; a further object being to provide a strip of the class defined wherein the flange portion is formed by folding the strip upon itself and stitching the folded parts together to form a neat and finished edge for said flange portion and to support the flange portion adjacent the coupling elements; a further object being to provide a finishing strip of the class described, which is adapted to cover one or both sides of the mounting strip of the stringer, and further wherein the finishing strip may be composed of one or more elements formed in the manner defined; and with these and other objects in view, the invention consists in a fastening device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a plan view of a part of a complete fastener made according to my invention.

Fig. 2 is a section on the line 2—2 of Fig. 1.

Fig. 3 is a view similar to Fig. 2 showing the position of the parts before the final stitching operation.

Fig. 4 is a transverse, sectional view through a modified form of strip which I may employ.

Fig. 5 is a view similar to Fig. 4 showing another modification; and,

Fig. 6 is a view similar to Fig. 4 showing another modification and showing only part of the construction.

It will be understood that my invention is applicable to stringers of fasteners of the class under

consideration, regardless of the specific type or form of coupling elements employed.

For the purpose of illustrating one use of my invention, I have shown in Fig. 1 of the drawing two stringers 10, 10a, each stringer being of the same construction and including interengaging coupling elements 11, 11a, on the respective strips which are coupled and uncoupled by a suitable slider 12 of conventional or any desired form and construction having a finger piece 13, the latter being movable longitudinally of the slider on a web or rib 14.

The stringers 10, 10a are of similar construction and the brief description of one will apply to the other. Each stringer consisting of a mounting tape 15 having an enlarged beaded edge portion 15a upon which the coupling elements 11 are mounted by compressing the yoke ends of said elements thereon or in any other manner commonly known in the art.

As shown in Figs. 1 to 3 inclusive, I employ a supplemental mounting and finishing strip 16 having a series of openings formed longitudinally thereof as at 17 by removing a number of the longitudinal threads or by preforming apertures or openings in the strip in accordance with conventional methods and as disclosed in prior patents granted to me, Number 18,406, Reissue, dated April 5, 1932 and Number 1,852,176, dated April 5, 1932, of which my present invention constitutes an improvement.

In the structure shown in Figs. 1 to 3 inclusive, the openings 17 are formed substantially centrally of the strip to provide an outer facing portion 16a and an inner facing portion 16b disposed on the top and under surfaces of the mounting strip 15 as will be apparent, the coupling elements 11 being passed through the openings 17 as clearly seen in Figs. 2 and 3 of the drawing. This disposes the transverse threads or the body of the strip between the openings between the coupling elements 11 and upon the bead 15a.

Adjacent one side of that part of the strip having the openings 17 therein is formed a projecting flange portion 18 by folding the strip upon itself and stitching the same as at 19. In mounting the strip 16 upon the stringer, the flange 18 is disposed on the outer surfaces of the coupling elements 11 and is held in contact therewith by arranging the stitching 19 adjacent the outer edge portion of the bead 15a and in stitching the side portions 16a and 16b together and to the strip 15 as at 20. In this connection, it will be understood that the flange portion 18 may be of any desired width but is preferably of such width as to cover the coupling elements 11 so as to dispose the flanges 18 of each stringer 10, 10a in abutting relation with respect to each other when the stringers are coupled together as seen at x in Fig. 1 of the drawing. It will thus be apparent that

the outer edges of the flanges 18 are disposed inwardly of the outer edges of the coupling parts or interengaging members of said elements.

Instead of using the side portion 16b as a facing for the strip 15, said side of the finishing strip may be terminated adjacent the coupling elements 11 in the manner illustrated in Fig. 6 of the drawing, the side 16b being made narrower and preferably folded upon itself and stitched to the mounting strip 15 and the side 16a on the stitching 20a. This will leave the corner and edge portions 21 of the coupling elements 11 exposed on the inner surface of the stringer for engagement with the slider. The finishing strip 15 in the structure shown in Fig. 6 will also include the flange portion 18 as in Figs. 1 to 3 inclusive.

In Fig. 4 of the drawing I have shown a slight modification wherein a finishing strip 22 is employed, and this strip consists of separate parts 23 and 24 forming the inner and outer side portions of the strip, the part 23 being similar to the side 16a and the part 24 similar to the side 16b. One side edge of the part 23 is folded upon itself to form a flange 18a similar to the flange 18 and the adjacent side edge of the part 24 is also folded upon itself and arranged within the fold of the part 23 and is stitched to said part as seen at 19a, the part 24 having the openings 17a formed therein adjacent the stitching so that the resulting finishing strip will in all general appearances, appear to be the same as that shown in Figs. 1 to 3 inclusive.

Aside from reinforcing the flange 18 and the adjacent parts of the finishing strip, the structure shown in Fig. 4 also makes it possible to use strip parts 23, 24 of different texture and/or color or both. For example, it may be desirable to have one type of strip on the outer surface of the stringer and another type on the inner surface thereon. This also applies to the structure shown in Fig. 5 which differs from that shown in Fig. 4 simply in eliminating the fold at the inner end of the strip part 24a, the latter merely resting upon the folded flange portion 18b of the strip part 23a and secured thereto by stitchings 19b. The part 24a has the openings 17b formed therein.

In the different forms of finishing strips herein disclosed, it will be apparent that these strips may be contrasting in color as well as texture to the mounting strip 15 so as to facilitate the manufacture of the stringers with the coupling elements thereon on a large scale and the storage of the same for supply, the latter being made by applying to the stringers strips of colors and textures suitable for the different merchandise upon which the fastening devices or units are employed as clearly set forth in my prior Patent Number 1,852,176. In this connection, it will be apparent that the fastener units are stitched or otherwise secured to the merchandise independent of the stitchings 20, 20a. It will also be understood that the separate side portions of the finishing strips may be of any desired width to partially or wholly cover the opposed side surfaces of the mounting strip 15.

In all cases, the apertured portions 17, 17a, 17b of the finishing strip serve to support the flanges 18, 18a, 18b in juxtaposition to or in constant abutting relation with the adjacent surfaces of the coupling elements eliminating any necessity of stitching the finishing strip to the bead 15a at said elements. In this connection, it will be understood that the stitching operation at 19,

19a, 19b is performed in the finishing strip prior to its attachment to the stringers.

It will be understood that while I have shown certain details of construction for carrying my invention into effect, that I am not necessarily limited to these details, and various changes therein and modifications thereof may be made within the scope of the appended claims without departing from the spirit of my invention or sacrificing its advantages.

Having fully described my invention, what I claim as new and desire to secure by Letters Patent, is:

1. A stringer for fastening devices of the class described comprising a mounting tape, a plurality of coupling elements attached to and spaced longitudinally of one edge of said tape and projecting therebeyond, a supplemental strip attached to said mounting tape and including a flange portion projecting beyond the edge of the mounting tape and covering part of the projecting portions of said coupling elements, said flange portion being formed by folding the supplemental strip upon itself and stitching the same together at the inner end of the flange portion and independent of said mounting tape, and the supplemental strip having a series of longitudinal openings disposed adjacent said flange portion through which the coupling elements of the stringer are adapted to pass.

2. A stringer for fastening devices of the class described comprising a mounting tape, a plurality of coupling elements attached to and spaced longitudinally of one edge of said tape and projecting therebeyond, a supplemental strip attached to said mounting tape and including a flange portion projecting beyond the edge of the mounting tape and covering part of the projecting portions of said coupling elements, said flange portion being formed by folding the supplemental strip upon itself and stitching the same together at the inner end of the flange portion and independent of said mounting tape, the supplemental strip having a series of longitudinal openings disposed adjacent said flange portion through which the coupling elements of the stringer are adapted to pass, and that portion of the supplemental strip intermediate the openings therein being disposed adjacent the outer edge of the mounting tape, and the supplemental strip being stitched to the mounting tape adjacent the inner ends of said coupling elements.

3. In separable fasteners of the class described comprising a mounting strip with coupling elements attached to one edge portion thereof and projecting beyond said edge in spaced relation with respect to each other, a finishing strip folded upon itself and stitched to form a flange portion, means whereby said finishing strip may be attached to the mounting strip to dispose said flange portion upon one side face of the protruding portions of said coupling elements and in juxtaposition thereto, said means comprising an apertured side edge portion on the finishing strip through which the coupling elements are passed, and said side edge portion being disposed upon the under face of the mounting strip and attached thereto.

4. In separable fasteners of the class described comprising a mounting strip with coupling elements attached to one edge portion thereof and projecting beyond said edge in spaced relation with respect to each other, a finishing strip folded upon itself and stitched to form a flange portion,

means whereby said finishing strip may be attached to the mounting strip to dispose said flange portion upon one side face of the protruding portions of said coupling elements and in 5 juxtaposition thereto, said means comprising an apertured side edge portion on the finishing strip through which the coupling elements are passed, said side edge portion being disposed upon the under face of the mounting strip and attached thereto on a line of stitching passing through the 10 corresponding part of the other side of the finishing strip.

5. In separable fasteners of the class described comprising a stringer consisting of a mounting member with a plurality of coupling elements attached thereto and projecting from said member in spaced relation with respect to each other, a finishing strip consisting of inner and outer parts disposed on the inner and outer surfaces of the 15 mounting member and attached thereto, and said parts being joined by a flange portion disposed adjacent and covering parts of the projecting portions of said coupling elements.

6. In separable fasteners of the class described comprising a stringer consisting of a mounting member with a plurality of coupling elements attached thereto and projecting from said member in spaced relation with respect to each other, a finishing strip consisting of inner and outer parts 20 disposed on the inner and outer surfaces of the mounting member and attached thereto, said parts being joined by a flange portion disposed adjacent and covering parts of the projecting portions of said coupling elements, and the 25 separate parts of the finishing strip being of contrasting texture.

7. In separable fasteners of the class described comprising a stringer consisting of a mounting member with a plurality of coupling elements attached thereto and projecting from said member in spaced relation with respect to each other, a finishing strip consisting of inner and outer parts disposed on the inner and outer surfaces of the mounting member and attached thereto, said 30 parts being joined by a flange portion disposed adjacent and covering parts of the projecting portions of said coupling elements, and the separate parts of the finishing strip being of contrasting color.

50 8. In separable fasteners of the class described comprising a stringer consisting of a mounting member with a plurality of coupling elements attached thereto and projecting from said member in spaced relation with respect to each other, a finishing strip consisting of inner and outer parts disposed on the inner and outer surfaces of the mounting member and attached thereto, said parts being joined by a flange portion disposed adjacent and covering parts of the projecting portions of said coupling elements and by longitudinally arranged openings through which the coupling elements are adapted to pass.

55 9. In separable fasteners of the class described comprising a stringer consisting of a mounting member with a plurality of coupling elements attached thereto and projecting from said member in spaced relation with respect to each other, a finishing strip consisting of inner and outer parts disposed on the inner and outer surfaces of the 60 mounting member and attached thereto, said parts being joined by a flange portion disposed

adjacent and covering parts of the projecting portions of said coupling elements and by longitudinally arranged openings through which the coupling elements are adapted to pass, said flange portion being formed by folding one part of the strip upon itself and stitching the same together and the other part joining the flange portion in an openwork body through which the coupling elements are adapted to pass. 5

10. In separable fasteners of the class described 10 comprising a stringer consisting of a mounting member with a plurality of coupling elements attached thereto and projecting from said member in spaced relation with respect to each other, a finishing strip consisting of inner and outer parts 15 disposed on the inner and outer surfaces of the mounting member, said parts being joined by a flange portion disposed adjacent and covering parts of the projecting portions of said coupling elements and by longitudinally arranged open- 20 ings through which the coupling elements are adapted to pass, said flange portion being formed by folding one part of the strip upon itself and stitching the same together and the other part joining the flange portion in an openwork body 25 through which the coupling elements are adapted to pass, and means for stitching the separate parts of the finishing strip together inwardly of said coupling elements to support the same in connection with said member. 30

11. In separable fasteners of the class described 35 consisting of two stringers adapted to be coupled and uncoupled, each stringer consisting of a mounting tape with coupling elements attached to one edge portion thereof and projecting beyond said edge in spaced relation with respect to each other, a finishing and mounting strip folded upon itself and stitched together inwardly of the fold to form a free flange portion, said strip being mounted directly upon said tape, means inwardly of said flange portion and adjacent said elements for securing the strip to said tape, said means being independent of the attachment of said tape and strip with a suitable support, the free flange portion of said strip being disposed 45 upon one side face of the protruding portions of said coupling elements, and means positioned between the inner and outer edges of the coupling elements for retaining said flange portion in juxtaposition to said elements. 50

12. A stringer unit for fastener devices of the class described comprising two mounting tapes, a plurality of coupling elements attached to and spaced longitudinally of one edge of one of said tapes and projecting therebeyond, the other tape 55 being mounted directly on the first named tape, means adjacent said elements for attaching the tapes together, said means being independent of the attachment of said unit to a suitable support, a flange portion on the second named tape 60 and projecting beyond the edge of the first named tape and covering part of the projecting portions of said coupling elements, means positioned between the inner and outer edges of the coupling elements for snugly supporting said flange portion upon said elements, and said flange portion being formed by folding one edge of the second named tape upon itself and stitching the same together at the inner end of the flange portion and independent of the first named tape. 65 70

DAVIS MARINSKY.
